CALIBRATING TOOL

Nick Mars, Sharon, Pa., assignor to Westinghouse Electric & Manufacturing Company, East Pittsburgh, Pa., a corporation of Pennsylvania

Application January 7, 1944, Serial No. 517,343

6 Claims. (Cl. 73—141)

My invention relates to a calibrating tool for measuring the pressure developed by a pressure-developing device or tool for applying an increasing pressure to a predetermined value on a workpiece operated by the pressure-developing tool being calibrated. My invention is applicable to calibrating the setting of a strap-stretching device of the character in which an increasing pressure is applied by the device until the pressure is increased to a predetermined value, at which value the strap-stretching device is automatically locked against further operation to prevent further increase in the tension applied to the strap stretched. Such a strap-stretching device is disclosed and claimed in my copending application, Serial No. 490,442, for Improvement in strap-stretching device, filed June 11, 1943, and assigned to the same assignee as this application.

In the strap-stretching device of my copending application, a hand-operated strap-stretching tool is employed for stretching or tightening steel straps or bands about a substantially solid mass of material, such as the core structures of electrical transformers where it is desirable to apply the band under a predetermined tension and to maintain a predetermined constant tension on the band about the core parts. The strap-stretching device causes tension to be applied to the two ends of the strap wrapped about the iron core and as the tool is operated, the tension of the strap is increased to a predetermined value, at which value the strap-stretching device releases a locking mechanism for locking the tool against further operation, thus holding the strap under a predetermined tension until it is fastened in its desired position at the desired tension. In order to provide for releasing the locking mechanism of the strap-stretching device at the desired predetermined tension on the metal or steel band being stretched, the calibrating tool of the present invention is employed. The pair of movable heads on the strap-stretching device which engage and cause the relative movement of the opposite ends of the strap being stretched are placed between relatively movable abutments in the calibrating tool of this invention and are operated until the locking mechanism of the strap-stretching device operates and the pressure at which this device operates is indicated, thus allowing for adjustments in the mechanism controlling the pressure at which the locking mechanism will release and permitting its ready adjustment to the desired value.

It is an object of this invention to provide a

calibrating tool that is adapted for measuring the pressure applied by a pressure-developing device or tool having two relatively movable heads that are mounted to move toward or from each other and are arranged to apply a pressure to the workpiece when forced in a direction away from each other.

It is a further object of the invention to provide a calibrating tool for calibrating the setting of a strap-stretching device that is adaptable for employment for stretching a metal strap about an article and is provided with means for locking the strap-stretching tool against further operation upon the application of a predetermined force upon the strap being stretched.

Other objects and advantages of my invention will be apparent from the following description of a preferred embodiment of the invention, reference being had to the accompanying drawing,

20 in which:

Figure 1 is a perspective view of the calibrating tool of the invention illustrated as used for calibrating a strap-stretching device corresponding to that illustrated and described in my above-25 identified copending application;

Fig. 2 is a vertical sectional view of the calibrating tool;

Figs. 3 and 4 are vertical and horizontal sectional views, respectively, through a shock-absorbing pressure cylinder comprising a part of the calibrating tool;

Fig. 5 is an enlarged detailed sectional view of a check-valve controlling an air passage to and from the pressure cylinder;

Fig. 6 is a view of parts of the tool partially disassembled;

Fig. 7 is a plan view of the base and guide cylinder mounted thereon with other parts of the calibrating tool removed.

Referring to the drawing, the calibrating tool comprises a base 1 shown as including a pair of channel members 2 and 3 upon one end of which a guide and calibrating member 4 is mounted, here illustrated in the form of a cylinder having a closed end 5 and adapted to receive and guide a calibrating sleeve 6 extending from a movable abutment 7 that is arranged to slide along the base of the calibrating tool. A main or calibrating spring 11 is provided within the calibrating sleeve 6 and the calibrating cylinder 4, one end of which engages against a centering member 12 adjacent the closed end 5 of the calibrating cylinder 4 and the opposite end of which engages against one wall of the movable abutment 7.

A fixed abutment 13 is also provided, fixedly mounted as by screws 14 to the base member 1 at the end thereof opposite the calibrating cylinder 4. A bore 15 is provided in the base of the abutment member 13, the walls of which, together with a piston 16, provide a closed air chamber between the piston 16 and the closed end 17 of the cylindrical bore 15, thus forming a pressure cylinder for a purpose to be later described. A guide rod 18 is provided, one end of which is attached to the piston 16 and the other end 19 of which is attached to the movable abutment 7, the rod 18 and piston 16 acting as a guide member for the movable abutment 7. The rod 18 extends through an opening in a plate or washer 21 illustrated as attached by screws 22 to the open end of the bore 15 in the fixed abutment member 13. A spacing spring 23 is shown about the guide rod 18 between the movable abutment member 7 and the plate 21 to limit the movement of the abutment 7 toward the right, as viewed in the drawing, thus spacing the two abutments 7 and 13 a predetermined minimum distance apart. A check valve device 31 is provided for controlling the communication between the chamber formed within the bore 15 and the outside atmosphere and as best shown in Fig. 5, comprises a bore 32 through the wall 33 of the abutment member forming the chamber and including a plug 34 at the inner end of the bore and a plug 35 at the outer end of the bore. An opening 36 is provided in the plug 34 communicating from the bore 32 with the outside atmosphere and an opening 37 having a conical valve seat 38 at its inner end is provided in the plug 35. A ball valve 39 is shown against the valve seat 38 that is normally held against its seat by the spring member 41, one end of which engages the ball valve 39 and the other end of which engages the plug 34.

Referring particularly to Fig. 1, a strap-stretching tool 53 is illustrated, having a pair of relatively movable heads 54 and 55 that are actuated by repeated relative movement of the handles 56 and 57 grasped between the palm and fingers of the hand and operated to effect, through the mechanism of the device 53, movement of the heads 54 and 55 away from each other. In the normal operation of the device for stretching a strap about an article, the two ends of the strap are engaged by the heads 54 and 55, the ends of the strap overlapping so as to draw them tight. Spring mechanism is provided in the handle of the tool 53 which, when a predetermined pressure is required to be applied between the handles 56 and 57 corresponding to a predetermined pressure applied to the strap being stretched, causes a locking mechanism 58 to be released and to lock the lever or handle 56 against further motion with respect to the handle 57. Since the strap-stretching device is not a part of the present invention, further detailed description of the operation of this device is deemed not necessary, it being sufficient to recognize that as the two heads 54 and 55 are moved in a direction away from each other in the normal operation of the device, the pressure required to move them increases until at some predetermined value locking mechanism 58 will trip and lock the tool against further operation.

In the calibrating operation, the two heads 54 and 55 of the strap-stretching device 53 are placed between the surfaces 51 and 52 of the abutments 7 and 13 of the calibrating device, as shown in Figs. 1 and 2, and the strap-stretching

device is operated in the usual manner by repeated gripping of the handles 56 and 57 between the palm and fingers of the hand thus causing the heads 54 and 55 of the tool to move away from each other. During this operation, the main or calibrating spring 11 is being compressed by movement of the abutment member 7 toward the left as viewed in the drawing until sufficient pressure is applied to cause the locking mechanism 58 of the tool 53 to trip. The value at which this tripping takes place is readable on the markings provided on the outer surface of the sleeve 6 as it enters the calibrating cylinder 4, thus indicating the setting of the tool being calibrated, that is, at what value of pressure the locking mechanism will trip. If this value of pressure is too high or too low, the mechanism contained in the handle of the strap-stretching tool 53 may be adjusted to correct for the proper value.

When the above-described operation is completed and the mechanism within the tool 53 holding the two heads 54 and 55 in their relatively separated positions is released thus permitting the head 54 to move toward the right, as shown in the drawing, the spring 11 will cause the abutment 7 to also travel toward the right. In order to prevent "back hammering" or sudden violent movement of the abutment 7 under the force of the spring 11, the piston 16 is provided which tends to compress the air contained within the bore 15 between the piston 16 and the end 17 of the abutment member, the check valve 31 retaining the air within the chamber, except as it gradually leaks past the piston 16, and preventing its passing therefrom while permitting free flow of air from the outside atmosphere into the chamber within the bore 15 when the piston 16 is moved toward the left, as shown in the drawing. The rod 18 also acts as a guide assisting the sleeve 6 in guiding the movable abutment member 7 in a straight line path along the upper surface of the base member of the tube.

It will be apparent to those skilled in the art that modifications may be made in the structure illustrated and described within the scope of my invention and I do not wish to be limited otherwise than by the scope of the appended claims.

I claim as my invention:

1. The combination in a calibrating tool, of a pair of spaced apart relatively movable abutment members arranged to receive between opposed surfaces thereon a pair of relatively movable heads of a strap-stretching tool for applying an increasing pressure on a strap upon movement of the heads of the tool away from each other, an elongated base upon which said pair of abutment members are mounted, one of the abutment members being fixedly mounted at one end of the base and the other being mounted for movement on a track provided on the base, a calibrating sleeve extending from the movable abutment member in a direction away from the fixed abutment member and a guide cylinder fixedly attached to the other end of the base for receiving said sleeve and having a closed end, a calibrating spring within the sleeve and guide cylinder having one end engaging the closed end of the cylinder and the other end engaging the movable abutment member resisting movement of it in a direction away from the fixed abutment member, indicating means responsive to the relative movement of the cooperating sleeve and cylinder and responsive to the relative movement thereof for indi-

cating the pressure applied between the abutment members by the strap-stretching tool being calibrated, a guide rod extending from the movable abutment member through a bore in the fixed abutment member for assisting in guiding the movable abutment member, and a spacing spring about the guide rod between the two abutment members.

2. The combination in a calibrating tool, of a pair of spaced apart relatively movable abutment members arranged to receive between opposed surfaces thereon a pair of relatively movable heads of a pressure-developing tool for applying an increasing pressure on a workpiece upon movement of the heads away from each other, a base upon which said pair of abutment members are mounted, one of the abutment members being fixedly attached to said base and the other being mounted for movement on a track provided on the base, a calibrating sleeve member extending from the movable abutment member and a guide member fixedly attached to said base for receiving said sleeve, a calibrating spring within the sleeve and guide members for increasing the pressure on the movable abutment member necessary to move it in a direction from the fixed abutment member, and indicating means responsive to the relative movement of the cooperating sleeve and guide means responsive to the relative movement of the sleeve and guide member for indicating the pressure applied between the abutment members by the pressure developing tool being calibrated, the fixed abutment member having a relatively large bore therein forming the walls of a chamber in alignment with the axis of movement of the movable abutment member and closed at the end remote from the movable member, a piston within said bore the inner end of which forms one wall of the chamber, and a piston rod connecting said piston to said movable abutment member and movable with said movable abutment member, a spacing spring between said movable abutment member and said fixed abutment member, and a check-valve for permitting free flow of air from the outside atmosphere to the chamber between the piston and the closed end of the cylindrical bore and for checking the flow of air from said chamber.

3. The combination in a calibrating tool, of a pair of spaced apart relatively movable abutment members arranged to receive between opposed surfaces thereon a pair of relatively movable heads of a strap-stretching tool for applying an increasing pressure on a strap upon movement of the heads of the tool away from each other, an elongated base upon which said pair of abutment members are mounted, one of the abutment members being fixedly mounted at one end of the base and the other being mounted for movement on a track provided on the base, a calibrating sleeve extending from the movable abutment member in a direction away from the fixed abutment member and a guide cylinder fixedly attached to the other end of the base for receiving said sleeve and having a closed end, a calibrating spring within the sleeve and guide cylinder having one end engaging the closed end of the cylinder and the other end engaging the movable abutment member for increasing the pressure on the movable abutment upon movement thereof in a direction from the fixed abutment member, indicating means responsive to the relative movement of the cooperating sleeve and cylinder and responsive to the rela-

tive movement thereof for indicating the pressure applied between the abutment members by the strap-stretching tool being calibrated, the fixed abutment member having a relatively large bore therein forming the walls of a chamber in alignment with the axis of movement of the movable abutment member and closed at the end remote from the movable member, a piston within said bore the inner end of which forms one wall of the chamber, and a piston rod connecting said piston to said movable abutment member and movable with said movable abutment member, a spacing spring between said movable abutment member and said fixed abutment member, and a check valve for permitting free flow of air from the outside atmosphere to the chamber between the piston and the closed end of the cylindrical bore and for checking the flow of air from said chamber.

4. The combination in a calibrating tool, of a pair of spaced apart relatively movable abutment members arranged to receive between opposed surfaces thereon a pair of relatively movable heads of a strap-stretching tool for applying an increasing pressure on a strap upon movement of the heads of the tool away from each other, an elongated base upon which said pair of abutment members are mounted, one of the abutment members being fixedly mounted at one end of the base and the other being mounted for movement on the base, a calibrating member extending from the movable abutment member in a direction away from the fixed abutment member and a guide member fixedly attached to the other end of the base for receiving said calibrating member, a calibrating spring having one end engaging the guide member and the other end engaging the movable abutment member for increasing the pressure on the movable abutment member necessary to move it in a direction from the fixed abutment member, indicating means responsive to the relative movement of the cooperating calibrating and guide members and responsive to the relative movement thereof for indicating the pressure applied between the abutment members by the strap-stretching tool being calibrated, a guide rod extending from the movable abutment member through a bore in the fixed abutment member for assisting in guiding the movable abutment member, and a spacing spring about the guide rod between the two abutment members.

5. The combination in a calibrating tool, of a pair of spaced apart relatively movable abutment members arranged to receive between opposed surfaces thereon a pair of relatively movable heads of a pressure developing tool for applying an increasing pressure on a workpiece upon movement of the heads away from each other, a base upon which said pair of abutment members are mounted, one of the abutment members being fixedly attached to said base and the other being mounted for movement on the base, a calibrating member extending from the movable abutment member and a guide member fixedly attached to said base for receiving said calibrating member, a calibrating spring for biasing the calibrating member and guide member and for increasing the pressure required on the movable abutment member to move it in a direction away from the fixed abutment member, and indicating means responsive to the relative movement of the cooperating calibrating member and guide member responsive to the relative movement of the calibrating member and guide member for indicating the pressure applied between the abutment mem-

bers by the pressure developing tool being calibrated, the fixed abutment member having a relatively large bore therein forming the walls of a chamber in alignment with the axis of movement of the movable abutment member and closed at the end remote from the movable member, a piston within said bore, and a piston rod connecting said piston to said movable abutment member and movable with said movable abutment member, and a check valve for permitting the free flow of air from the outside atmosphere to the chamber between the piston and the closed end of the cylindrical bore and for checking the flow of air from said chamber.

6. The combination in a calibrating tool, of a pair of spaced apart relatively movable abutment members arranged to receive between opposed surfaces thereon a pair of relatively movable heads of a strap-stretching tool for applying an increasing pressure on a strap upon movement of the heads of the tool away from each other, an elongated base upon which said pair of abutment members are mounted, one of the abutment members being fixedly mounted at one end of the base and the other being mounted for movement on the base, a calibrating member extending from the movable abutment member in a direction away from the fixed abutment member and a guide member fixedly attached to the base and

having a bore for receiving said calibrating member and having a closed end, the calibrating member also having a bore in alignment with the base in the guide member, a calibrating spring having one end within the bore in the calibrating member and the other end within the bore in the guide member for biasing the movable abutment member toward the fixed abutment member and for increasing the pressure on the movable abutment member necessary to move it in a direction from the fixed abutment member as its movement from the fixed abutment member increases, indicating means responsive to the relative movement of the cooperating calibrating member and guide member and responsive to the relative movement thereof for indicating the pressure applied between the abutment members by the strap-stretching tool being calibrated, the fixed abutment member having a relatively large bore therein forming the walls of a chamber in alignment with the axis of movement of the movable abutment member and closed at the end remote from the movable member, a piston within said bore the inner end of which forms one wall of the chamber, and a piston rod connecting said piston to said movable abutment member and movable with said movable abutment member.

NICK MARS.
